FUSE SWITCH

Application filed August 5, 1929. Serial No. 383,734.

Our invention relates to new and useful improvements in high tension fuse switches. More particularly it relates to a universal fuse switch which is adjustable to accommodate different length fuses for various voltages and types.

High tension power lines are used with a large variety of voltages. Each different voltage requires a different length fuse and accordingly a different bracket to accommodate the various fuses. This fact places a heavy burden on the manufacturer of this equipment since he is required to stock all sizes, and in the case of fuse brackets this means a large number of patterns from which to make the castings.

There is another variable factor in the cross arms of the line poles. These arms come in different sizes and also call for different bracket accommodations.

With the foregoing in mind, the principal object of our invention is to provide a universal fuse bracket to accommodate different length fuses.

A further object is to provide guides for the fuse terminals so that the proper engagement of the fuse is always effected.

A still further object of the invention is to provide attaching means on the fuse for a hook stick so that the hook stick engages the fuse adjacent the working point.

Additional objects of the invention are to form the bracket with sectional arms, one member of each arm being rigidly carried by the bracket and the other member being in frictional engagement with the first member and under normal conditions held in proper fuse engaging position but adapted to be displaced or give under severe shocks or recoil force so as to absorb said shocks and prevent damage or injury to the bracket or rigid parts thereof.

When a fuse is blown, the gases escaping through the lower open end of said tube produce recoil which causes said tube to be forced upwardly, thereby displacing it from its contact members. If rigid stops are provided on the brackets to check this upward movement of the tube the recoil force is transmitted to said stops, causing breakage of the latter, or

of the arms of which said stops form part. In either case the mounting is seriously damaged, requiring repairs and replacement of the damaged parts and causing disablement of the line. By forming each arm of the bracket of two parts jointed and frictionally held together, the fuse carrying members of the jointed arms are adapted to yield under severe shocks and move upwardly with the fuse tube, thereby absorbing the shock and preventing injury to the mounting and said tube. With the foregoing and other objects in view, our invention consists in certain novel features of construction and arrangement of parts, hereinafter more fully described and claimed, and illustrated in the accompanying drawings, in which—

Figure 1 is a side elevational view of our improved fuse switch.

Figure 2 is a cross sectional view taken on line 2—2 of Figure 1.

Figure 3 is a detail showing the method of attaching the fuse to the bracket.

Figure 4 is a detail showing the method of positioning the fuse to close the circuit.

Figure 5 is a cross section taken on line 5—5 of Figure 1.

Figure 6 is an enlarged side elevational view of the lower one of the brackets showing the lower end of the insulator in cross section.

Figure 7 is a horizontal cross sectional view taken on line 7—7 of Figure 6.

The numeral 1 in the drawings indicates the cross arm of a high tension line pole. 2 is a fuse switch bracket, the base 3 of which is fastened to arm 1 by U-bolt 4. The upper leg of the U-bolt engages lug 5 on bracket base 3, while the lower leg engages slot 6 in the same member. The engagement of the lower leg of the U-bolt in slot 6 permits the use of several sizes of U-bolts and consequently provides for attaching the bracket 2 to various sizes of cross arms.

The upper portion or arm 7 of bracket 2 extends outwardly from the base 3 and terminates in the usual insulator carrying yoke 8. Insulator 9 is mounted in the yoke 8 by suitable clamp members and tie bolts which latter extend through the clamp members and have their ends secured to said yoke. In

the lower portion of the bracket base 3 a second slot 10 is located. An outwardly projecting arm 11 is mounted on the lower portion of bracket base 3 through the intermediary of nut and bolt 12, which bolt engages slot 10 and is adapted to position arm 11 at any height on base 3 within the limits of this slot. Arm 11 carries insulator 13 in a manner similar to arm 7.

10 Pins 14 having disks 15 on their lower ends are cemented into the underside of each insulator 9 and 13. Terminal carrying arms 19^a and 19 are provided with similar disks 16 which are preferably held in frictional yielding contact with their companions 15 by nuts and bolts 17 forming trunnions.

15 This provides a pivotal connection between the terminal arms 19 and 19^a and the supporting insulators 9 and 13, respectively, the purpose of which is hereinafter described. The usual wire terminal connection means and fuse contact holders consisting of bent copper clips 18 are mounted on the outer ends of these terminal carrying arms.

20 Depending from the outer end of the lower terminal carrying arm 19^a is an integral vertically disposed plate member 20. This plate lies in the same plane as the main body of the terminal carrying arm 19^a and is provided 25 in its forward edge with a rearwardly presented hook 21, thereby forming a hook shaped recess 21^a.

25 The fuse proper consists of upper and lower terminals 22 and 23 which are joined by a cartridge or horn fiber tubing 24. The portion 25 of lower terminal 23 is squared for engagement with contact holder 18. Below this squared portion are a pair of spaced, vertically disposed rearwardly projecting flanges 26. Looking at the fuse as it is 30 shown in Figure 1 when positioned in the bracket, the lower corners of flanges 26 carry a horizontally disposed pin 27 and the upper corners are provided with aligned openings 28. A stud 29 threaded into terminal 23 secures the lower end of the fuse wire 30. This fusible element 30 has its upper end secured within the upper terminal 22, and extends downwardly therethrough and outwardly through the lower open end of said tube.

35 The upper terminal 22 is also provided with a squared portion 31 for engagement with its contact holder 18. A stud 32 engages the upper end of the fuse wire 30 interiorly of the terminal. The eye portion 33 is integral with the terminal and projects from its extremity.

40 To apply the fuse to the bracket, a hook stick 34 is used. The hook is inserted in openings 28 of flanges 26 and the pin 27 of lower terminal 23 is placed in the hook-shaped recess 21^a of the lower terminal carrying arm (see Fig. 3). The hook stick is then disengaged and inserted in eye 33 of the upper ter-

5 minal. As the upper terminal is swung into place with pin 27 as the pivot, the flanges 26 engage therebetween plate 20 and insure proper alignment of both terminals with their respective contact holders 18 (Fig. 4). The hook stick is thus attached to the fuse adjacent the working point at all times which is a distinct advantage since the length of these sticks is sometimes as much as twenty feet. Heretofore it has been found very difficult to 75 insert in position the free end of a fuse swinging on the end of a twenty-foot pole and our improved construction greatly facilitates such operation.

80 To adjust the bracket for the accommodation of different length fuses, the lower arm 11 is raised or lowered, as the case may be, in slot 10. Nut and bolt 12 are utilized to lock this arm in position. Any movement of arm 11 after the bracket has been once set throws 85 the upper and lower contact holders 18 out of alignment. However, this alignment is restored by shifting the terminal arms 19^a and 19 at their pivotal connections with the pins 14. In assembling, the insulators 9 and 13 90 may be rotated in their yokes to obtain the correct positions of the pins 14 but when once set there is no occasion to shift the positions of these insulators.

95 A very advantageous feature of our improved high tension fuse switch lies in forming the terminal arms 19^a and 19 separate from pin 14. This pin is held in the insulator by a cement which takes approximately sixty 100 hours to set. Heretofore it has been customary to form the entire terminal carrying arm in one piece and while the cement was setting it was not unusual for the weight of the arm to shift its position in the 105 insulator so that when the cement set the part was not properly aligned and could not be used. It can be readily understood that there is much less opportunity for our pin 14 to shift during the setting of the cement and even if shifting does take place the aforementioned adjustments can compensate for it. Consequently there are no insulator 110 assembly units rejected because of improperly positioned cemented parts.

115 The forward edge of plate 20 is inclined forwardly and upwardly above hook 21 and terminates in a straight portion 35 which, when the fuse is in position, contacts with the body of the lower terminal 23, so that the pin 27 is firmly held in the extremity of recess 21. This same portion 35 serves to prevent the introduction of the fuse in reversed or 120 upsidedown position due to the offset location of pin 27. Where reversal of the fuse is possible, frequently the upper contact 18 is 125 damaged by the hook stick while the fuse is being inserted.

130 Disks 15 and 16 are preferably formed dish-shaped so that only the edges thereof come in contact, the body portions of said disks

being spaced and providing a certain degree of resiliency for maintaining said disks in proper contact engagement. Preferably the contacting edges of the disks are slightly separated to insure proper engagement of the disks so that only a comparatively heavy shock or recoil movement liable to cause damage will cause the displacement of said disks relatively to each other.

10 5 By forming the terminal carrying arms sectional, whereby members 19^a and 19 are yieldable relatively to pins 14, any severe blows or recoil shocks imparted to said members 19^a and 19 are absorbed thereby and are prevented from being imparted to pins 14 or insulators 9 and 13. Thus the rigidly supported parts are protected against breakage and the life and usefulness of the device is considerably prolonged. Also the interruption of service incidental to the breakage of parts is eliminated.

15 20 It is to be understood that minor changes in the form, size, and construction of the various parts of our device can be made and substituted for those herein shown and described without departing from the spirit of our invention as set forth in the appended claims.

We claim:

30 35 1. In a line disconnecting switch, an insulator carrying arm, a second insulator carrying arm adjustable with respect to said first-mentioned arm, insulators carried by said arms, and switch terminals pivotally supported from said insulators.

2. In a line disconnecting switch, a bracket, an insulator carrying arm formed with and fixed in relation to said bracket, a second insulator carrying arm mounted on said bracket and movable along the bracket with respect to said first-mentioned arm, means for holding said second insulator arm in position, insulators carried by said arms, and means adapted to position a movable switch member between said insulators.

40 45 3. In a line disconnecting switch, a switch bracket including a base and an insulator carrying arm, a second insulator carrying arm adjustably connected to said base and movable with respect to said first-mentioned arm, in fixed distance relation to said base, insulators carried by said arms, and stationary switch terminals carried by said insulators.

50 55 4. In a line disconnecting switch, a switch bracket including a base, an insulator carrying arm projecting angularly from, and formed integrally with the base, a second insulator carrying arm adjustably connected to said base and movable along said base, toward and away from said first-mentioned arm, insulators carried by said arms, switch contacts and a switch blade carried by said insulators.

55 60 5. In a line disconnecting switch, a bracket, a pair of spaced insulators carried by said

bracket, pins mounted in said insulators, switch terminal arms having terminal portions, and carried by said pins, the terminal portions thereof adapted for pivotal movement in a common plane, and a movable switch member carried between said terminal portions.

6. In a line disconnecting switch, a bracket comprising a base, and an upper insulator carrying arm formed on the base, a lower insulator carrying arm adjustably mounted on said base and movable in respect to said upper arm, insulators mounted on said insulator arms, and terminal arms carried by said insulators, said terminal arms being pivotally jointed intermediate their ends.

7. In a line disconnecting switch, an insulator carrying bracket, insulators carried by said bracket, and switch blade carrying arms mounted in said insulator, said arms being pivotally jointed intermediate their ends.

8. In a line disconnecting switch, a bracket, a pair of spaced insulators carried by said bracket, pins mounted in said insulators, terminal carrying arms, means for adjustably angularly associating said arms with said pins, and a switch blade member mounted on said terminal carrying arms.

9. In a line disconnecting switch, a pair of spaced insulators, one of said insulators being adjustable toward and away from its companion, terminal carrying arms mounted in said insulators, switch terminals on said arms, and means for maintaining alignment of said arms and terminals upon adjustment of said movable insulator.

10. In a line disconnecting switch, a pair of spaced insulators, one of said insulators being adjustable toward and away from its companion, terminal carrying arms mounted in said insulators, and a pivotal joint in said arms intermediate their ends to restore proper alignment upon movement of said insulators.

11. In a line disconnecting switch, a base, a pair of spaced insulators, means for regulating the spacing of said insulators, terminal carrying arms carried by said insulators, switch terminals on said arms, adapted for disposition at an angle to said base, and means permitting an angular movement, for purposes of aligning adjustment, of said terminals.

12. In a line disconnecting switch, a bracket, a separable U-bolt for connection of said bracket to the cross arm of a pole, and means in said bracket to accommodate different sizes of U-bolts for connection to cross arms of various cross sectional proportions.

13. In a line disconnecting switch, a bracket having a slot therein, a lug on said bracket, a U-bolt having spaced legs, one of which is adapted to engage said lug, and a pole cross arm adapted to be snugly engaged by the

main body of said U-bolt, the lower leg of said U-bolt engaging said slot adjacent said cross arm.

14. In a fuse switch, a pair of spaced terminal carrying arms, a plate on one of said arms having a hooked recess therein, a fuse cartridge including spaced terminals, and a tube extending between said terminals, a pair of spaced flanges projecting laterally of one of said terminals, and one thereof being provided with an aperture for a fuse-manipulating tool, a pin between said flanges adapted to engage said hooked recess with said flanges extending laterally of said plate to guide said terminals into proper engagement with said terminal carrying arms.

15. In a line disconnecting switch, a bracket, switch terminals, jointed terminal carrying arms and a removable switch blade having contact members for introduction into said terminals, a hooked member formed integral with one of said arms at a point beyond the terminal carried thereby, a pair of flanges on one of said contact members, and a pin extending between said flanges and spaced laterally of the blade axis, from the contact member by which it is carried, said pin being adapted to engage said hooked member to pivotally connect said blade to said member.

16. In a line disconnecting switch, a pair of spaced arms, switch contact members carried by said arms, a plate on one of said arms having a hooked recess formed in the lower portion thereof, a movable switch member including upper and lower terminals, spaced flange members on said movable switch member, movable into guiding engagement with said plate, and a pin disposed between said flange members, said pin adapted to be introduced into said hooked recess to position said movable switch member, said pin being laterally offset from said lower terminal, and thereby adapted for movement into the extremity of said recess by the abutment of the upper portion of said plate with the main body of said lower terminal upon swinging said fuse into position.

17. As a new article of manufacture, a fuse switch bracket having spaced arms, insulators and switch terminals carried by said arms, one of said arms being movable toward and away from its companion for the accommodation of different length fuse cartridges, and means providing for angular adjustment of one of said switch terminals, in a plane parallel to that of the switch bracket.

18. As a new article of manufacture, a switch frame for a line disconnecting switch, having brackets each insulated from the frame and provided with a swinging joint to enable their adjusting movement distantly and angularly relative to each other and to a switch blade member, whereby said

brackets are adapted to carry disconnecting switch parts of different sizes.

19. In a device of the class described, a switch frame, a bracket mounted thereon for linear adjustment along the frame, an insulator carried by said bracket, and a carrying arm for switch parts, said arm being pivotally mounted on said insulator. 70

20. In a device of the class described, an electric high tension load carrying member adapted to be cemented in and carried by an insulator, said member being separably and yieldably joined adjacent its point of connection with said insulator to permit adjustment thereof and also to yield under severe shocks and a recoil. 75

21. A line disconnecting switch bracket for high tension transmission lines, including in combination with a metallic frame having lateral extensions, an insulator carried by each extension, a member secured to said insulator and depending therefrom, said member having an apertured enlargement, a terminal carrying member having an apertured enlargement cooperating with the first enlargement to constitute a swinging joint, means for clamping said enlargements together, whereby said terminal carrying member may be angularly adjusted relative to said first named member. 80

22. A fuse switch bracket for high tension transmission lines comprising a frame having lateral extensions, an insulator carried by each extension, a rigidly mounted member depending from each insulator, and a terminal carrying arm secured at one end to the extremity of said member, said arm being frictionally held in position and being adapted to become displaced when the fuse is subjected to severe recoil, thereby absorbing the shock incidental thereto and preventing displacement of the fuse. 100

23. In a switch mounting for a line disconnecting switch, the combination with a bracket, of a pair of spaced arms, a plate formed integral with one of said arms and having its forward edge formed with a rearwardly presented hook, a movable switch member including upper and lower terminals engageable with said arms, a pair of parallel spaced plates adapted to engage therebetween the plate of said arm, thereby aligning said movable switch member with both of said arms, and a pin offset laterally of the movable switch member, and extending between said pair of spaced plates for engaging the said hook and pivotally supporting said movable switch member. 110

24. In a mounting for high tension disconnecting switches, the combination with a frame, of a pair of spaced terminal engaging arms carried thereby, a vertically disposed plate formed integral with one of said arms and terminating in an upwardly presented hook, a switch blade member includ- 125

ing terminals engageable with said arms, one of said terminals having formed integral therewith a pair of spaced parallel plates for engaging therebetween said hook plate, 5 thereby forming an aligning guide for said blade member at least one of said parallel plates being formed to receive a fuse manipulating tool, for lifting the blade member onto and away from said hook, and a pin 10 extending between said spaced parallel plates for engaging said hook and forming a pivotal mounting for said blade member.

25. In a mounting for high tension fuse switches, the combination with a frame, of a 15 pair of spaced terminal engaging arms carried thereby and adjustable relatively to each other, said arms being yieldable from normal positions under severe shocks to absorb the recoil when the fuse is blown, a vertically disposed plate formed integral with one of said arms and terminating in its forward edge with a rearwardly and upwardly presented hook, a fuse including terminals engageable with said arms, one of said terminals being provided with a vertically disposed slot for receiving said vertically disposed plate whereby said fuse is held in

alignment with said terminal engaging arms, and a pin extending across the lower end of said slot for engaging said hook and forming a pivotal support for said fuse and one of said terminal engaging arms. 70

26. In a device of the class described, the combination with an insulator adapted to be carried by a bracket, of a pin embedded in said insulator and depending therefrom, the lower end of said pin being provided with a circular apertured enlargement, a terminal engaging member provided at one end with a circular apertured enlargement having a frictional contact with the first enlargement, and bolt and nut means extending through the apertures of said enlargements for clamping the latter together and holding said terminal engaging arm in adjusted position, said terminal engaging arm being yieldable under severe impacts so as to absorb the shock produced thereby and prevent injury to the fuse switch assembly. 75

In testimony whereof we hereunto affix our signatures this 27th day of June, 1926.
